UNITED STATES PATENT OFFICE.

GEORGE W. MORRIS, OF RACINE, WISCONSIN.

DRIVING MECHANISM.

No. 893,539.

Specification of Letters Patent.

Patented July 7, 1906

Application filed April 29, 1903. Serial No. 426,801.

To all whom it may concern:

Be it known that I, GEORGE W. MORRIS, a subject of the King of Great Britain, residing at Racine, in the county of Racine, State of Wisconsin, have invented certain new and useful Improvements in Driving Mechanism, of which the following is a specification, reference being had to the accompanying drawings.

10 This invention relates to improvements in driving mechanism and while particularly designed for use in connection with traction-engines may be employed with other machines.

15 The object of the invention is to provide an improved construction of driving gears of different diameter, and to provide novel means for quickly causing either of said gears to be clutched or locked to the drive-shaft so as to 20 rotate therewith while the other of said gears is out of clutching or locking engagement therewith, and to as quickly move said clutching or locking means out of engagement with either of said gears. I accomplish this object by the means shown in 25 the drawings and hereinafter specifically described.

In the drawings:— Figure 1 is a central vertical section through my improved mechanism, the drive-shaft, however, being shown 30 in elevation; and Fig. 2 is an end view, the devices being partly broken away.

Referring to the several figures of the drawings, in which corresponding parts are indicated by like reference characters,—3 indicates a shaft having a squared end 4. This shaft is adapted to be driven in any suitable manner.

5 indicates a gear-wheel having an extended hub 6 loosely mounted on the shaft 3, the projecting end of the hub abutting, in the construction shown, against the shoulder caused by the formation of the squared portion 4 of the shaft. The peripheral teeth of 40 this gear-wheel are indicated by 7. The web or body of this gear-wheel 5 is of considerable thickness, as clearly shown, and there is formed in one face thereof around the hub 6 a deep annular recess 8 the wall of which is provided with teeth thus forming an internal gear 9 with which is adapted to mesh a pinion as hereinafter described.

10 indicates a wide annular flange projecting laterally from the inner face of the web or body of the gear-wheel 5, such flange being located a short distance from the recess 8.

11 indicates a second gear-wheel which is of smaller diameter than the gear-wheel 5. Its peripheral teeth are indicated by 12. The rim of this wheel 11 on which the teeth 12 are formed project for quite a distance to one side of the web or body of the wheel, such projection of the rim being towards the first-mentioned gear-wheel 5. The inner face of this laterally-projecting rim is smooth and fits over and rests upon the smooth outer face of the annular flange 10 carried by the gear-wheel 5. The edge of the laterally-projecting rim is turned outward to form a narrow flange 13.

14 indicates a ring, which, as best shown in Fig. 2, is made in two sections, which ring is secured by bolts 15, or in any other suitable manner to the face of the web or body portion of the gear-wheel 5. The inner edge of 75 this ring 14 projects opposite the narrow flange 13 before described and thus effectively retains the gear-wheel 11 connected to the other gear-wheel 5, but free to rotate independently of the rotation of said gear-wheel 5. The gear-wheel 11 is provided with a large central opening 16 the wall of which is provided with teeth constituting an internal gear 17—such internal gear corresponding in size and number of teeth to the internal gear 85 of the gear-wheel 5.

18 indicates a clutch member formed, as shown, of a pinion that is slidably mounted on the extended hub 6 of the gear-wheel 5 and of a size to adapt its teeth to mesh with either of the internal gears 9 and 17. As shown, the two gear-wheels 5 and 11 are so constructed and arranged as to leave between their webs or body portions a considerable space into which the pinion 18 may be moved when it is desired to have it out of mesh with either of the internal gears.

19 indicates a sleeve connected to the pinion 18 and surrounding the shaft 3, the opening through the outer end portion 20 of said sleeve being squared to adapt it to fit over and yet be slideable upon the squared end 4 of said shaft. The sleeve and its attached pinion are by this construction always rotated with the shaft. 21 indicates a ring secured in any suitable manner around the end portion 20 of the said sleeve, the attachment of the ring being, in the construction shown, by screws 22. A short distance from this ring is formed a shoulder on the 190 surface of said end portion 20 whereby is left an annular space 23 adapted to receive

a collar or yoke at the end of a shifting lever that may be employed to slide the sleeve 19—20 and attached pinion 18 on the shaft in order to cause said pinion to mesh with 5 either one of the gear-wheels or to be brought to a position between them. The shifting mechanism referred to is not shown, as the construction of such devices is well understood.

10 24 indicates a stop at the outer end of the squared portion 4 of the shaft against which the end of the sleeve will abut when drawn back to bring the pinion 18 into full engagement with the internal gear 17. This stop, 15 as shown in Fig. 2, is in the form of a ring which is held in place by a pin 25 passing through it and the shaft.

With the device in use it will be understood that the teeth 7 and 12 of the gear-wheels 5 and 11, respectively, will be in engagement with a smaller and larger gear, respectively, on a shaft to be driven, and, accordingly as it is desired to drive such last-mentioned shaft faster or slower, the 25 pinion 18 will be shifted on the extended hub 6, in the manner already described, to bring it into engagement with either the internal gear 9 or internal gear 17. When it is desired to drive neither of the gear-wheels 5 or 11 the pinion will be shifted to bring it between said two gears, as shown in Fig. 1. When either of the gear-wheels 5 or 11 is being positively driven through the pinion 18, there is no driving power being exerted by 35 the other, and owing to the smooth surfaces of the outer face of the flange 10 and the inner surface of the projecting or flange-like rim of the gear-wheel 11 that are in contact with each other, the relative movement of 40 these two parts will cause but little friction and consequently but little loss of power.

As will be understood from the description of the construction of the mechanism, the several parts can be readily and easily assembled or separated, and when assembled as shown constitute a cheap, simple, compact and durable device by which a driven shaft can be instantly set in motion at either one of two speeds.

50 What I claim as my invention and desire to secure by Letters Patent is:—

1. In a device of the class described, the combination with a shaft and a wheel loosely mounted on said shaft and provided with an 55 internal gear and a laterally-extending annular flange, of a second wheel loosely supported on said flange and also provided with an internal gear, and a clutch device secured to and slidably mounted upon said shaft and 60 adapted to be moved into engagement with either of said internal gears.

2. In a device of the class described, the combination with a shaft and a wheel loosely mounted thereon and having an internal 65 gear and a laterally-extending annular flange,

of a second wheel also provided with an internal gear and loosely supported on said flange; means for retaining said second wheel on said flange, and a clutch device secured to and slidably mounted upon said shaft and 70 adapted to be moved into engagement with either of said internal gears.

3. In a device of the class described, the combination with a shaft and a wheel loosely mounted thereon and having an internal gear 75 and a laterally-extending annular flange, of a second wheel also provided with an internal gear and loosely supported on said flange, a ring secured to the face of the first-mentioned wheel and engaging a projecting edge of the 80 rim of said second-mentioned wheel, and a clutch device secured to and slidably mounted upon said shaft and adapted to be moved into engagement with either of said internal gears.

4. In a device of the class described, the combination with a shaft and a wheel loosely mounted thereon and having an internal gear and a laterally-extending annular flange, of a second wheel also provided with an internal 90 gear and loosely supported on said flange, the webs or body portions of said wheels being separated so as to leave a space between them, and a clutch device secured to and slidably mounted upon said shaft and adapted to be moved into engagement with either of said internal gears or to be moved into the 95 said space between the said two gear-wheels.

5. In a device of the class described, the combination with a shaft and a wheel having 100 an extended hub portion that is loosely mounted on said shaft, said wheel being provided with an internal gear and also with an annular flange that extends from one face of the wheel, of a second wheel also provided 105 with an internal gear and loosely supported on said flange and having a large central opening, a clutch slidably mounted on said hub portion, and a sleeve attached to said clutch, said sleeve extending through the said opening in said second-mentioned wheel and having 110 a sliding but non-rotatable engagement with said shaft.

6. In a device of the class described, the combination with a shaft and a wheel loosely 115 mounted on said shaft, said wheel being provided with a laterally-extending annular flange and having a recess in one face, of a second wheel loosely supported on said flange, said second wheel being provided 120 with a central opening, and a clutch device secured upon said shaft and adapted to be moved into either the recess in said first-mentioned wheel or the central opening of the second-mentioned wheel.
